ELECTRONIC GROUNDING APPARATUS

Roy A. Riddle, Summit, N. J., and Theodore J. Mesh, Easthampton, Mass.; Pearl Kilpatrick Riddle, administratrix of said Roy A. Riddle, deceased, and said Theodore J. Mesh assigns to Gilbert & Barker Manufacturing Company, West Springfield, Mass., a corporation of Massachusetts

Application June 15, 1950, Serial No. 168,282

2 Claims. (Cl. 250—27)

1

This invention relates generally to safety means for use, when loading tank trucks with gasoline, oil and the like, to guard against the fire hazard from static electricity.

More particularly, the invention relates to a safety means, which can be used to show when the grounding cable is not connected to the tank of the tank truck, as by giving a signal, audible or visible, or to prevent loading of the tank, if desired.

The general object of the invention is to accomplish the result electrically but with the use of such minute currents in the grounding cable, that no fire or physical hazard is presented.

More particularly, the invention has for an object the provision of an electrical operator for effecting signals or any other work, and to control this operator electronically, energizing it when the grounding cable is electrically connected to the tank of the truck, characterized in that the electrical capacity of the tank with reference to the ground may be utilized to unbalance an electronic control circuit and cause the operator to be energized.

The invention will be disclosed in connection with one illustrative example of it in the accompanying drawings, in which:

Fig. 1 is a diagram showing the apparatus and its electrical circuits;

Fig. 2 is a side elevational view of the housing for the apparatus;

Fig. 3 is a top plan view of such housing as it appears with the cover removed; and

Fig. 4 is a fragmentary wiring diagram showing a modification in the form of the electrical operator.

Referring to these drawings and first to the diagrammatical illustration of the invention in Fig. 1, it is desired to energize an electrical operator of any suitable and desired kind, whenever a grounding wire is properly connected to the tank of a tank truck. This operator may, for example, be used to cause a signal, either visual or audible, to be given or to control a valve in a pipe line used to supply the tank with oil, or in other ways. As herein illustrated, the operator is shown as a relay 1, operable when energized, to actuate a suitable switch, moving the blade 2 into engagement with the contact 3 in this case. This switch may control any suitable electrical circuit to perform the work desired. But the relay coil may, when energized, cause the desired work to be performed mechanically as well as electrically. Also, the relay is not in all cases necessary although it is

generally desirable because of the low operating current available in the present apparatus.

In general, the relay 1, or other electrical operator, is controlled by an electronic tube, in this case a triode 4, the relay being in series with the plate 5 and cathode 6 in a circuit supplied from a suitable source of electricity. The tube 4 is normally non-conducting and the relay 1 is not energized. A bridge circuit 7, to the input terminals 8 and 9 of which is impressed a radio frequency voltage of low amplitude, has its output terminals 10 and 11 respectively connected to the grid 12 of tube 4 and to the ground. Normally, the impedances in the bridge circuit are balanced and no voltage appears at the output terminals 10 and 11. The cable, used to ground the tank of the truck, is indicated at 13. One end of this cable is connected to the input terminal 9 of the bridge circuit and through one arm of such circuit to the output terminal 11 of the bridge circuit and thus to the ground. The other end of cable 13 is adapted to be electrically connected to the tank of the truck. When the cable is so connected, the electrostatic capacity of the truck with reference to the ground becomes connected into one arm of the bridge circuit, unbalancing the latter and causing a radio frequency voltage to appear at the output terminals of the bridge circuit, and this causes the triode 4 to become conducting, whereby the relay 1 is energized.

Power for the apparatus may be secured from a 115 volt, 60 cycle, alternating current source, adapted to be connected to the terminals 14 and 15. The ungrounded terminal 14 is connected by a wire 16 to a half-wave rectifier 17, which may be of the selenium cell type. This rectifier is connected by a wire 18 to one terminal of a current-limiting resistor 19 of say 30 ohms resistance, and the other terminal of the latter is connected by a wire 20 to the terminal 21 of a voltage divider, comprising a 10,000 ohm resistor 22 and a 1000 ohm variable resistor 23 connected in series. The other terminal 24 of the voltage divider is connected by a wire 25 to power terminal 15. The plate-cathode circuit of triode 4 is supplied from the terminal 21 and the variable terminal 26 of the voltage divider. A wire 27 connects terminal 21 to one end of relay coil 1 and the other end of the latter is connected by a wire 28 to the plate 5. A wire 29 connects cathode 6 to the terminal 26. The terminal 24 is connected to ground by a wire 30. Bias for the grid 12 is derived from the voltage divider between the terminals 24 and 26. The grid 12 is connected

by a wire 31 to the output terminal 10 of the bridge circuit and the other output terminal 11 of the latter is connected by a wire 32 to wire 30. A condenser 33, say of .003 mfd. capacity, is connected across the wires 29 and 30 and provides a high frequency path from the cathode and wire 29 to wire 30 and the ground. The relay coil 1 may, for example, have a resistance of 5000 ohms. A condenser 34, of say .1 mfd. capacity, is bridged across the relay coil 1 for the purpose of smoothing out the pulses of the voltage impressed on the relay.

The bridge circuit includes an inductance 35 in that arm which extends between the terminals 9 and 11. This inductance may, for example, be a 10 millihenry, powdered iron core, radio frequency choke. It forms part of the connection from grounding cable 13 to the ground and provides a low impedance path for static electricity and a high impedance path for high frequency current. It enables the radio frequency signal to be superposed on the grounding cable 13. A similar inductance 36 is provided in that arm of the bridge circuit which extends between the terminals 9 and 10. A condenser 37, of say .001 mfd. capacity, is provided in that arm of the bridge circuit which extends between the terminals 10 and 8 and a similar condenser 38 is provided in the arm which extends between the terminals 8 and 11. The impedances 35 and 36 and 37 and 38 are normally balanced and no voltage appears at output terminals 10 and 11.

It is deemed preferable to shield the grounding cable 13 and a shield is conventionally shown at 39. This shield is grounded, as indicated. When the cable 13 is not connected to the tank truck, it forms with its shield a condenser which is bridged across the inductance 35. A condenser 40 of approximately the same capacity as that of cable 13 and shield 39, in this case .005 mfd., is bridged across the inductance 36. Variable condensers 41 and 42, of from 100 to 580 mmf. are respectively bridged across the inductances 35 and 36 for tuning purposes. These "padder" condensers are adjusted, after the grounding cable has been attached to the bridge circuit and before it is attached to the tank truck in order to balance the bridge circuit.

The radio frequency voltage of low amplitude may be obtained in any suitable way. For example, it may be produced by a triode 43 which functions as an oscillator. This triode has a plate 44, cathode 45, grid 46 and a heating filament 47 for the cathode. The cathode 45 is connected by a wire 48 to negative power wire 25 and by a wire 49 to one end of the grid coil 50. The other end of the latter is connected by a wire 51, a resistor 52, of say 50,000 ohms, and a wire 53 to the grid 46. A condenser 54 of say .003 mfd. capacity, is bridged across resistor 52 and a condenser 55, of say .001 mfd. capacity, is bridged across the grid coil 50. The plate 44 is connected by a wire 56 to one end of the feed back coil 57 and the other end of the latter is connected by a wire 58 to the positive power wire 20. A filtering condenser 59, of say 10 mfd. capacity, is bridged across the power wires 20 and 25. The pick up coil 60 of the oscillator is connected by wires 61 and 62 to the input terminals 8 and 9, respectively, of the bridge circuit. The grid coil 50, feed back coil 57 and pick up coil 60 are coupled. These three coils may, for example, be 10 millihenry, powdered-iron-core, radio-frequency chokes. The oscillator described is designed to produce a relatively low voltage, say 6

volts, at a frequency of 50,000 cycles per second.

The heating filament 47 for the cathode 45 of triode 43 and the filament 48 for heating the cathode 6 of triode 4, are connected in parallel 5 in a circuit, comprising wires 63 and 64, connected to the secondary 65 of a transformer 66, the primary 67 of which is connected across the power wires 16 and 25. The secondary voltage may, for example, be 6.3 volts.

In practice, all the elements described, with the exception of the grounding cable 13 and its shield 39, are enclosed in an explosion-proof metallic casing, such as shown at 70 in Fig. 2. The power wires for connection to the terminals 14 and 15 and the wires for connection to the terminals 71 and 72, which as shown in Fig. 1 electrically connect with the switch blade 2 and its contact 3, respectively, enter the casing 70 through a conduit 73. The shield 39 is connected 10 by a coupling 74 to the casing 70 and thereby grounded. On the outer end of ground wire 13 is a suitable clip 75 for electrical connection to the tank of the tank truck. The casing 70 has a removable cover 76 to enable access to the terminals 14, 15, 71 and 72 for connection thereto of the wires in conduit 73 and for adjustment of the condensers 41 and 42 and for adjustment of the variable resistor 23 to secure the proper bias for tube 4. The casing 70, with attached ground cable 13 and shield 39 and the various circuits and elements described, can be supplied as one unit to a refinery, for example, for use at a loading station, so that all that has to be done is to connect the terminals 14 and 15 to a suitable 15 power source, the casing 70 to the ground, and the terminals 71 and 72 to whatever device it is desired to operate, such as a signal, audible or visible, as desired. Or a valve in the oil supply line may be opened by electrical means connected 20 to terminals 71 and 72. In place of the relay, a small neon tube 77 might be used, as shown in Fig. 4, and directly operated by the small current available.

The triodes 4 and 43 may be combined in one 25 tube, such as a 6SN7 or 5692 tube, indicated at 78 in Fig. 3.

The values of resistance, capacity and inductance, given herein, are capable of considerable variation. They are what we consider as optimum values for the purpose and therefore desirable for the practice of the invention in the best way. But they are capable of variation and the invention is not to be limited by the values given.

In use, the ungrounded and grounded sides of 30 the power source are respectively connected to the terminals 14 and 15. This will energize the apparatus. The oscillator produces a radio frequency signal of low amplitude and this is impressed on the input terminals 8 and 9 of the bridge circuit 7. With the impedances of such circuit balanced, no voltage appears at the output terminals 10 and 11 and the tube 4 is non-conducting because of its negative grid bias. A radio frequency signal is imposed on the grounding cable 13. When the operator attaches the grounding cable 13 by means of clip 75 to the tank truck, the capacity of the tank with reference to the ground becomes electrically connected into the bridge circuit across the inductance 35. This unbalances the bridge circuit. The amplitude of the radio-frequency signal on the grounding cable 13 is reduced to a small percentage of its original value and a radio-frequency signal appears at the grid of tube 4, rendering this tube conducting and thereby en-

abling the relay 1 to be energized from its current source. The relay 1 pulls in to operate the signal, or other desired device, to show that the grounding cable has been properly connected to the tank of the tank truck. Any static electrical charge will be discharged through the grounding cable 13 and inductance 35 to the ground. In case the relay controls a valve in the oil loading line, the valve will open when the relay 1 is energized. Then, should the clip 75 on the grounding cable become detached from the tank truck, the valve will automatically close. Of course, the relay could equally well be arranged to cause the signal to be given when it is deenergized, in which case a signal could be given on detachment of said clip or other failure of the tank grounding means.

The apparatus is designed to fail safely. Failure of the current source, the rectifier, transformer, the oscillator or the electronic tube will prevent the relay from operating.

While the apparatus is designed to respond to the connection into the bridge circuit of the electrostatic capacity of the truck with reference to the ground, it will be clear that it will respond to anything that will unbalance the bridge circuit. This is necessary so long as the tank trucks continue to use grounding chains because the grounding chain of the tank truck may be left down, when the apparatus is connected to the truck, and form an alternate path to the ground, which in some cases may have substantial resistance and in other cases, substantially none. Thus, the effect of a truck grounding chain that is left down, may be that of a resistor in parallel with inductance 35 or it may act to short circuit said inductance. In either case, the balance of the bridge circuit will be upset and the relay 1 will operate as described.

Thus, there is provided a safe electrical means for energizing an electrical operator of any suitable or desired kind, when the grounding cable at the tank loading station is electrically connected to the tank of a tank truck to be serviced. The invention is particularly characterized in that the cable used to connect the tank truck to the ground also connects the tank into a balanced bridge circuit and serves as a control means to change the balance in such circuit, and cause a suitable electrical operator to be energized.

What is claimed is:

1. An electronic grounding apparatus for use with tank trucks and the like, comprising, a bridge circuit having four arms with an impedance in each arm, means for impressing on the input terminals of said circuit a radio frequency voltage of low amplitude, a grounding cable connected at one end to one input terminal of said circuit and adapted for connection at its other end to the tank of the truck, one output terminal of said circuit being grounded, the impedance in that arm of said circuit which extends between the last-named input terminal and the last-named output terminal including an inductance coil of low resistance to conduct static charge

from said tank through said inductance from said cable to the ground, an electrical operator to be energized when said grounding cable is electrically connected to the tank, an electronic tube controlling said operator, a circuit including said operator and the plate and cathode of said tube and adapted for connection to a source of electricity, a connection from the other output terminal of the bridge circuit to the grid of said tube, said impedances in the bridge circuit being balanced when said cable is not connected to the truck and there being then no voltage at the output terminals of said circuit, said tube being normally non-conducting and rendered conducting when the balance in the bridge circuit is upset by the connection of said cable to the tank truck and the resulting inclusion in said circuit in parallel with said inductance of the capacity between the tank and ground, whereby the operator is energized.

2. An electronic grounding apparatus for use with tank trucks and the like, comprising, a bridge circuit having four arms with an impedance in each arm, means for impressing on the input terminals of said circuit a radio frequency voltage of low amplitude, a grounding cable connected at one end to one input terminal of said circuit and adapted for connection at its other end to the tank of the truck, one output terminal of said circuit being grounded, the impedance in that arm of said circuit which extends between the last-named input terminal and the last-named output terminal including an inductance coil of low resistance to conduct static charge from said tank through said inductance from said cable to the ground, a grounded shield for said cable, said cable and shield forming a condenser bridged across said inductance, an electrical operator to be energized when said tank is grounded, an electronic tube controlling said operator, a circuit including said operator and the plate and cathode of said tube and adapted for connection to a source of electricity, a connection from the other output terminal of the bridge circuit to the grid of said tube, said impedances in the bridge circuit being balanced when said cable is not connected to the truck and there being then no voltage between the output terminals of said circuit, said tube being normally non-conducting and rendered conducting when the balance in the bridge circuit is upset by the connection of said cable to the tank truck and the resulting inclusion in said circuit in parallel with said inductance of the capacity between the tank and truck, whereby the operator is energized.
